PANEL

Harry B. Denman, Birmingham, Mich., assignor
to Detroit Gasket & Manufacturing Company,
Detroit, Mich., a corporation of Michigan

Application January 7, 1935, Serial No. 782

10 Claims. (Cl. 154—46)

The present invention relates to panels and more particularly those associated with the interiors of motor vehicles where a permanent, attractive appearance must be preserved under relatively difficult and widely varying conditions of temperature and moisture, as well as shock and vibration.

Thus an object of the invention is to produce a panel substantially free of warping tendencies, and which is not affected by moisture and heat or cold.

Ordinarily, panels are made by indenting a base material to produce a raised configuration, over which the trim cloth is adhered. Frequently, it is difficult to produce a uniform indentation as where the configuration includes sharp outlines and moreover, the pressed-in portion or portions exert a normal tendency to return or "fade" under conditions of usage. As a result, a uniformly neat and attractive appearance for a given design is sometimes impossible and when the indentations contract or "fade", the cloth becomes loose and saggy, i. e., it separates from the panel body.

These obstacles are overcome by the present invention wherein the sharpest configuration is easily molded and, moreover, is solid or substantially solid so that (1) there is neither difficulty in forming a uniform contour nor (2) any possibility of objectionable "fading". Moreover, the moldable material exhibits no tendency to warp or distort and where used with a base sheet, it has sufficient strength to overcome the possibilities of warping or distortion of the base under extreme conditions.

Further characteristics of the moldable material are its temperature and moisture resistance, and a resilience resembling hard rubber which is compensatory under conditions of use. Further, the moldable material is such that the trim cloth may be easily adhered by any satisfactory, resistant adhesive so that at all times a neat and permanently attractive appearance is presented.

Referring to the drawing:

Figure 1 is an elevation of a panel in accordance with the present invention;

Figure 2 is a sectional view of the panel;

Figure 3 is an elevational view partly broken away with the trim cloth removed;

Figure 4 is a sectional view of a laminated panel material;

Figure 5 is a sectional view similar to Figure 4 showing the panel provided with configurations or raised portions;

Figure 6 is a sectional view of a further form of panel material;

Figure 7 is a sectional view similar to Figure 6 showing the panel provided with configurations or raised portions;

Figure 8 is a sectional view of a modification; this panel may also be used in connection with Figures 2, 4, 5 and 6.

Figure 9 is a sectional view of a further modification; this panel may also be used in connection with the structures shown in Figures 2, 4, 5 and 6.

Referring to the drawing, I have illustrated in Figure 1 at 10 a panel in accordance with this invention, in position on the door of an automobile. It is to be understood that the panel of this application is not restricted to motor cars but may be used with any other structure.

Referring to Figures 2 and 3, this panel comprises a base 11 of any suitable stiff material, 20 but preferably a stiff paper or fiber board of suitable gauge or thickness. The fiber board is preferably rendered waterproof by incorporation in the fibers of a suitable water resistant agent, or it is impregnated or coated with such a water 25 resistant material. There are any number of satisfactory waterproofing agents commercially available for this purpose which form a continuous film.

The panel 10 is provided with a layer 12 of 30 moldable material forming a raised configuration. As shown in Figures 1, 2 and 3, the riser consists of a strip or spaced strips which may be continuous about the margin of the base as shown, or discontinuous and applied upon any desired spaced areas of the base 11, i. e. the sectional designs or raised portions are attached to the base without covering the whole area thereof.

The configuration is therefore produced by superposing on the base 11 and adhering thereto a layer 12 molded to any desired form and positioned with respect to the base, i. e., covering any required areas thereof, to give the appropriate predetermined contour and appearance.

The layer 12 of moldable material is preferably an unvulcanized mixture of reclaimed rubber, fibers, and a suitable plasticizing, waterproofing agent such as asphalt, for example, gilsonite. 50 This mixture, on setting, has the resilience and firmness characteristics of hard rubber. It may be premolded and united to the base 11 by a suitable adhesive or directly molded upon the base 11. The adhesive is applied either to the 55

base or to the moldable composition or both, or the mixture may be of itself adhesive.

In some cases, a vulcanizing agent is used in the mixture and adherence obtained by vulcanization of the layer 12 to the base 11.

The area of the layer 12 of moldable material, is in some cases, coextensive with the base 11, as in Figures 4 and 5. Again the layer 12 comprises a single narrow strip or strips, the latter 10 in some cases in connected relation, superposed upon and adhered to the base. Where, as in Figures 2, 5 and 7, the risers are in multiple, they are formed integral with and connected by a relatively thin web 13, or as shown in Figure 9, 15 the risers are adhered to a separate sheet or web 13' of larger area than the web 13; the risers may likewise be formed integral with the larger web 13' as shown in Figure 2, for example. The layer 12, including in some cases a web 13 or 13', 20 in any instance, is adhered to the base in the manner already described.

Over the board 11 having the layer 12 comprising the configuration or raised portions is superposed a trim cloth 14 as in Figure 2. This trim cloth is adhered to the board 11 and the layer 12 substantially throughout the area of the cloth, as shown in Figure 2, and its edges are carried over and adhered to the back of the board as at 16. A neat and clean-cut fit is thus produced 30 bringing out sharply the attractive contour of the board. The adhesive may be applied to the cloth or to the layers 12, 13, or both; again the rubber fiber-asphalt mixture may be inherently adhesive or be vulcanizable, so as to secure, in 35 all cases, the required coextensive adhesion of cloth to the board and its contoured surface.

In some cases a cloth finish is not used and instead thereof a coating of temperature and weather resistant lacquer or varnish of an appropriate color is employed.

Likewise, the layer 12 whether of spaced configurations or a coextensive layer has sometimes a suitable color incorporated therein, whereby a trim cloth or coating need not be used.

Referring to Figure 4, the board 11 is coated or covered with a coextensive, relatively thin layer 12 of the moldable material which may be plain if desired, i. e., devoid of raised portions or configurations.

Referring to Figure 5, the board 11 shown in Figure 4 is provided with a coextensive layer 12 of moldable material having integral molded riser portions to give the desired configuration 12'. The layer 12 may be preliminarily molded to the 55 contour shown, or any other desired contour, or the raised portions 12' may be molded to form after or simultaneously with the application of moldable material to the board 11.

In Figure 6, there is illustrated a plain layer 60 of moldable material which, in some cases, is quite satisfactory for panel purposes exhibiting freedom from warping, and resistance to the factors of heat and moisture to which panels are normally subjected. In Figure 7, the layer 12 is thicker, but otherwise similar to the layer 12 illustrated in Figure 5, the moldable material being formed with the integral raised portions or configurations 12'.

Where the layer 12 is coextensive with the 70 board 11 as shown in Figures 4 and 5, or a web 13 or 13' is used as shown in Figures 2 and 9, the layer or web, as the case may be, is preferably thinner than the layer of moldable material 12, as shown in Figures 6, 7 and 8.

75 In Figure 8, I have illustrated a layer 12 similar

to that shown in Figure 6, but embossed or pressed to have configurations 17 formed therein. This layer 12 may be (1) used alone; (2) superposed upon and united to a board 11, or (3) superposed upon and united to another moldable material 5 layer 12, i. e., a plain base as shown in Figure 6, producing a very acceptable panel, in all cases. The moldable material, as stated, is heat and moisture resistant and permanent, i. e., the hollow indentations 17 do not exhibit any tendency 10 to return or fade such as is frequently encountered where a fibre board is pressed in or em-bossed.

In Figure 9, the layer 12 includes the raised portions or configurations either integral with 15 the web 13' or adhesively united thereto. It is to be noted that the area of the layer 12 in Figure 9 is somewhat greater than the area of the layer 12 in Figure 2, the web whether integral or separable with respect to the raised portions extend- 20 ing laterally from opposite sides thereof as shown at 18.

It is to be observed that the molded raised portions of the layer 12 as shown in Figures 2, 5, 7 and 9 are solid and this, of course, assures that 25 there will be no substantial contraction or return, i. e., so-called "fading" of the configurations such as would destroy the adherence of the cloth and produce a looseness or sagging to mar the appearance of the panel.

The permanency and strength of the moldable layer 12 insures a similar resistance to contraction or fading in the case of a panel constructed in accordance with Figure 8.

The moldable material of the layer 12, as here- 35 tofore stated, upon setting, has the resilience and firmness of hard rubber. When united to the board 11 or to another layer of moldable material 12, it acts to reinforce the base and retard any possible distortion or warping. Because of 40 the resilience and flexibility of the material, it is compatible with the ordinary stiff paper board sheets and will flex and bend sufficiently after the manner of such sheets to permit the panel to be properly positioned and attached on the 45 body structure.

With respect to a panel comprising the layer 12, as shown in Figure 8, either used alone or combined with a board 11 or a base layer 12 of 50 moldable material, the firmness and strength of the configurated layer, whether it be coextensive or simply have a strip form is quite marked. While I prefer that the configurations be solid, as shown in Figure 2 for example, there are many instances where a structure of the type 55 shown in Figure 8 is useful either alone or in combination as described.

It is to be noted that the configurations or contours are very easily produced, are permanent, and the rubber fibre, asphalt mixture is compat- 60 able with most adhesives whereby the moldable mixture is readily united to the base and to the trim cloth 14. It is understood, of course, that whenever the panels described will be covered with the trim cloth 14, that this member will be 65 adhesively united to the board and to the moldable mixture upon the board, so that the adhesive union is co-extensive with the area of the board and configurations and the cloth. A neat, close fitting appearance, bringing out sharply and 70 clearly a uniform contour, is obtained and since there is but little opportunity for warping in view of the reinforcing action of the layer 12 upon the base and substantially no possibility of fading due to the permanent character of the 75

layer 12, this adhesive union and hence the nice appearance of the panel is preserved.

In preparing the reclaimed rubber-fibre-asphalt mixture, the reclaimed rubber and gilsonite, for example, are fed into a suitable rubber mill and worked cold for about five minutes. As one example, thirty parts of rubber to fifteen parts of gilsonite are used. After a thorough mixing, the fibres such as ground paper or any other fibrous material or scrap, and/or comminuted cork, are added gradually in the amount of about fifty parts. The mixing operation consumes about twenty minutes.

In addition to the fibrous material, a filler, such as whiting, is used in some cases in approximately five parts.

After the complete mixing, in the course of which the temperature, due to working, may go up to 150° F., the mixture is taken to a calendering machine and sheeted out to the desired gauge. The mixture, as will be understood, is warm and the temperature of the calendering rolls may be as high as 150° F. as desired. Following calendering, the sheets are cold-pressed or molded to the desired form while warm. The warming temperature or the temperature of the mixture should not exceed 150° F.

The unvulcanized moldable or plastic mass will harden to the condition of ordinary hard rubber without employment of a vulcanizing agent and at normal atmospheric temperature and pressure, i. e., no heating or other treating of the material is required in order to cure or set it. This, it will be appreciated, is of great importance in manufacture, whether the layer 12 is preformed with configurations or coated upon the base sheet and the configurations molded thereon.

Thus, in carrying out the invention, a coextensive layer or a strip layer or a layer of any desired configuration may be preliminarily formed and then adhesively united to the base, whether it be a board 11 or a layer 12 of the moldable material. Again, the moldable material may be applied to the base and the configuration then produced on the layer 12 simultaneously with its adhesion to the base or thereafter.

In some cases, I apply a configuration layer or a coextensive layer to each side of the base. It is to be noted that where the layer 12 is coextensive with the base, that it is of less thickness than the base and the configurated portions. Of course, the thickness of the layer 12 may be of any desired gauge.

While I have referred to an unvulcanized moldable mixture and prefer this, since the composition described on setting is hard and resilient after the manner of hard rubber, and quite strong, in some cases I utilize a vulcanizing agent in the mixture such as sulphur. A somewhat similar final set product is obtained and where the vulcanizing agent is present, in some cases it is possible to eliminate the use of an adhesive for securing the layer 12 to the base or the trim cloth to the layer 12, since the adhesive union will be obtained by the vulcanizing action, i. e., the rubber fiber composition will be vulcanized with the panel in assembled relation.

The board 11 employed is preferably one constructed to be very resistant to warping and, as stated, waterproof. The moldable composition described possesses characteristics similar to that of the board, so as to be compatible therewith whereby flexing or expansion and contraction will not result in cracking of either layer nor breaking down of the adhesive union.

In this connection, a board of varying pliancy may be used and likewise the percentage ratio of materials forming the moldable layer 12 may be varied. For example, the layer 12 may have increased or decreased stiffness by changing the fibre content.

In all cases, a panel structure is obtained which is (1) highly resistant to warping, (2) free from any "fading" characteristics, and (3) weather resistant and vibration resistant. All of these factors are important when it is considered that the panel of the present invention, because of the moldable material, is susceptible of providing any desired contours regardless of the complicated or sharp angle characteristics required.

I also prepare a mixture comprising rubber, an asphalt such as gilsonite, and cork, the cork being comminuted or granulated and comprising substantially 10% by weight, i. e., approximately 35% by volume. This mixture also comprises in some cases rubber, an asphalt, fibrous material, for example paper fibres, and comminuted cork in the percentage or weight just specified.

As stated, a facing is applied to the surface of the panel such as (1) a trim cloth, or (2) a resistant coating or finish of suitable color, or (3) the layer 12 whether it (a) covers the whole area of the base or (b) is applied to spaced areas thereof has incorporated therein a suitable color. When the layer 12 includes a color and is applied to leave exposed portions of the base, the base may have incorporated therein or be coated or finished with the same or a contrasting color.

Further modifications of the invention may, of course, be made all of which are comprehended within the scope of the appended claims.

I claim:

1. A panel comprising a relatively stiff base, a layer of a moldable composition material adhered to said base and forming a raised portion or configuration, and a trim cloth overlying said sheet and said layer of moldable material and united to said sheet.

2. A panel comprising a layer of stiff sheet material and a layer of a composition of rubber and fibers including a waterproofing agent united to said sheet at spaced points and overlying spaced areas of the sheet.

3. A panel comprising a layer of stiff sheet material, a layer comprising a composition of rubber and fibers including a waterproofing agent, said layer having integral therewith a configuration or raised portion extending above the plane of the sheet.

4. A panel comprising a layer of stiff sheet material, a coextensive layer comprising a moldable composition of rubber and fibers including a waterproofing agent, portions of said layer being molded and raised above the plane of said sheet.

5. A panel comprising a layer of stiff sheet material, a layer comprising a composition of rubber and fibers including a waterproofing agent, said layer having a configuration or raised contour extending above the plane of the sheet and a web portion adhered to the surface of the sheet.

6. A panel comprising a layer of a composition of rubber and fibers including a waterproofing agent, portions of said layer being indented to form configurations extending laterally with respect to the plane of the layer.

7. A panel comprising a layer of a composition of rubber and fibers including a waterproofing agent, portions of said layer being indented to form configurations extending laterally with respect to the plane of the layer.

spect to the plane of the layer, and a base to which said layer is united.

8. A panel comprising a relatively stiff base, a layer of a moldable, resilient, composition material including rubber adhered to said base and forming a raised portion or configuration at spaced points overlying spaced areas of the base.

9. A panel comprising a layer of stiff sheet material, a layer comprising a composition of rubber, comminuted cork and fibers including a wa-

terproofing agent, said layer having integral therewith a configuration or raised portion extending above the plane of the sheet.

10. A panel comprising a layer of stiff sheet material, a layer comprising a composition of rubber, comminuted cork and including a waterproofing agent, said layer having integral therewith a configuration or raised portion extending above the plane of the sheet.

HARRY B. DENMAN. 10
